UNITED STATES PATENT OFFICE

MOE GOLDMAN, OF ATLANTA, GEORGIA

DESIGN FOR A SERVING SCISSORS

Application filed May 3, 1930. Serial No. 35,486. Term of patent 14 years.

To all whom it may concern:

Be it known that I, MOE GOLDMAN, a citizen of the United States, residing at Atlanta, in the county of Fulton and State of Georgia, have invented a new, original, and ornamental Design for Serving Scissors, as shown in the accompanying drawing and described in the following specification.

In the accompanying drawings:

Figure 1 is a front elevation and Figure 2 is a side elevation of a pair of serving scissors exhibiting my design.

I claim:

The ornamental design for a serving scissors as shown.

MOE GOLDMAN.
